CLAIM

The ornamental design for a sports-themed battle standard, as shown and described.

DESCRIPTION

FIG. 1 is a front view of a sports-themed battle standard, as shown and described;

FIG. 2 is a side view one-hundred-and-twenty degrees (120°) from the view in FIG. 1 thereof;

FIG. 3 is a side view one-hundred-and-twenty degrees (120°) from the view in FIG. 2 thereof;

FIG. 4 is a rear view thereof;

FIG. 5 is a top view thereof; and,

FIG. 6 is a bottom view thereof.

In the drawings, the broken lines illustrate environment and form no part of the claimed design.
